UNITED STATES PATENT OFFICE.

GUY S. LANE, OF PHILADELPHIA, PENNSYLVANIA.

OIL CUP.

Application filed October 23, 1920. Serial No. 419,036.

To all whom it may concern:

Be it known that I, GUY S. LANE, a citizen of the United States, residing at Philadelphia, in the county of Philadelphia and

3 State of Pennsylvania, have invented certain new and useful Improvements in Oil Cups, of which the following is a specification.

This invention relates to oil cups.

10 One of the primary objects of my invention is to provide a simple and improved automatic oiling device; and improved means for locking the parts and another of the objects of the invention consists in the 15 provision of means whereby a control valve mechanism of the type shown and described may be applied to an elbow cup.

The foregoing, together with such other objects as may hereinafter appear, or are incident to my invention, I obtain by means of a construction which I have illustrated in preferred form in the accompanying drawings, wherein:

Fig. 1 is directed to an oil cup embodying my improvement; Fig. 2 is a plan view of a detail of my improvement; Fig. 3 is a plan view of a modification of such detail; Fig. 4 is a section illustrating the application of the control valve to an elbow type of cup; and Fig. 5 is a section illustrating how the oiler of Fig. 1 may be used for elbows.

Referring now to Figs. 1 and 2, the reference numeral 7 designates the cup, provided 35 at the top with a snap lid 8 of any preferred type and at the bottom with a hollow plug 9, the upper end of which is expanded in the neck of the cup forming as a whole the body of the cup. The plug is externally threaded at the bottom and is also provided with the valve seat 10. The valve stem 11 is adapted to be inserted and removed through the plug 9 and the inside diameter of the plug is such that the valve 40 stem 11 may swing or oscillate partially unseating the valve to permit of seepage of oil past the valve 12. The valve is normally held in the position shown in Fig. 1 by means of the spring 13, the lower end 45 of which is seated within the plug 9 and the upper end of which bears against the adjustable weight 14 which has threaded engagement with the upper portion of the valve stem. The weight 14 causes the valve to 50 respond more freely to the vibrations of the automobile or other machine to which

the oil cup is applied and the degree of opening is dependent upon the position of the weight and the compression of the spring. 60

In order to hold the weight in any position of adjustment and at the same time preserve ease of adjustment, I provide the following mechanism. The weight 14 is formed or provided with an upstanding lip 65 or ring-like member 15 which is preferably integral with the weight. A portion of this lip is sheared or otherwise separated from the weight and pressed inward to provide a spring locking nose 16. By this arrangement the weight will be held in any position of adjustment and at the same time it can be readily turned so that adjustment of the weight can be easily done. To facilitate adjustment and assembly the valve is provided with a slot 17 for the reception of a screw driver or other suitable tool. 70

In cases where it is desired to provide a more positive lock for the weight 14, I form a tongue 16' as shown in Fig. 3 from inspection of which it will be seen that the tongue is sprung inwardly so that an edge of the end thereof bears against the threads in such manner as to permit the valve stem to be readily turned in the direction of the arrow but 80 when it is attempted to back off the weight or to turn the valve stem in the reverse direction, the end of the tongue will take a bite in the thread and thus positively lock the weight. 90

Where the tongue is formed from a member integral with the weight, I prefer to make the weight of any material which will provide the requisite springiness for the locking tongue. I have found iron or mild 95 steel suitable.

Referring now to Fig. 4, it will be noted that the plug 9' is provided with an elbow 17, the flow of oil to which is controlled by the valve 12, as before. In order to permit of the assemblage of the parts, I provide a boss 18 in line with the passage in the body of the plug, and I aperture and internally thread this boss for the reception of a removable plug 19. By this arrangement the 100 valve and valve stem can be inserted from the bottom. 105

If desired, instead of providing a special form of elbow cup, the form shown in Fig. 1 may be utilized by employing an elbow 110 member 20, enlarged at 21 and internally threaded to fit the threaded end of the plug

9. The other end 22 is reduced to standard size and externally threaded. This is an arrangement which readily permits of assembly and replacement.

for holding the valve in closed position, there being an aperture for the insertion and removal of the valve, and a means for closing said aperture. 10

5 I claim:

In an oil cup having an elbow, the combination of a valve for controlling the flow of oil from the oil cup to the elbow, means

In testimony whereof, I have hereunto signed my name.

GUY S. LANE.
